TUBE RING

Augustus P. McCormick, Alton, Ill., assignor to
Standard Oil Company (Indiana), Chicago, Ill.,
a corporation of Indiana

Application October 13, 1930, Serial No. 488,261

1 Claim. (Cl. 257—262)

This invention relates to an improvement in tube rings and more particularly to tube rings for the heat exchanging tubes of preheaters and similar equipment.

It is common practice in the manufacture of preheaters, heat exchangers or similar equipment to increase contact between the tube and the heating media by means of cast iron rings, fins or gills. Cast iron rings are objectionable on steel tubes because of their different coefficients of expansion and because of the poor union which is obtained between the steel and the cast iron. When tubes used for preheating petroleum are equipped with cast iron rings or gills it has been found that a strain is set up in the encompassed portion of the tube and that this strain results in abnormal corrosion. It has also been found that the "shrunk-on" rings do not give as good heat transfer as welded rings and that the heat transfer from the ring to the tube in the latter case occurs through the weld, the rate being too low to indicate that the total surface of the ring is actually utilized. The object of my invention is to avoid all strains and corrosion in structures of this character and at the same time to obtain maximum heat transfer between the ring and the pipe. A further object is to increase the heat-transfer area of a pipe without materially increasing its weight. A further object is to reinforce the preheater pipe.

The rings may be simply and cheaply applied to a tube by bending or swaging a bar of metal around a tube by suitable jaws operated by a reciprocating piston. In order to obtain maximum heat conductivity I prefer to weld the ring to the tube over a relatively wide area so that the weld will be as wide as the thickness of the ring. It should be particularly noted that my improved rings are closed and that they are spaced on the tube so that maximum reinforcement and heat transfer may be obtained with a minimum weight and a minimum amount of material. By welding steel to steel I obtain a more perfect union and I avoid the difficulties which would ensue from the use of metals having different coefficients of expansion. Thus with alloy steel tubes such as high chromium tubes, I prefer to use rings of similar material to avoid expansion strains.

My invention will be more clearly understood from the detailed description of a preferred embodiment which is illustrated in the accompanying drawing wherein similar parts are designated by like reference characters, and wherein

Figure 1 is a side elevation of my improved machine for mounting rings on tubes.

Figure 2 is an end elevation of said machine, showing the swaging mechanism in its initial position.

Figure 3 is a similar view showing the swaging mechanism in its second position.

Figure 4 is a similar view showing the swaging mechanism in the third position.

Figure 5 is the same view showing the final position of the swaging mechanism.

Figure 6 is a transverse section through my reinforced tube showing the welded ring structure.

Figure 7 is a horizontal section showing rings welded from one side only, and

Figure 8 is a similar section showing the rings welded from both sides.

The steel tube 10 may be of any suitable steel or alloy, and is preferably a tube of the type generally used for oil preheaters in the petroleum industry. This tube may be mounted on suitable chucks 11 and 12, which may be supported and rotated in any desired manner. A steel bar 13 is formed with tapered ends 14, the length of the bar and the degree of the taper being adjusted so that the tapered ends will meet when the bar is swaged around the tube. I preferably heat the bar for the swaging operation and I position the hot bar under the tube by means of a fork comprising supports 15 mounted on each end of a cross piece 16 which is centrally attached to a suitable handle 17.

Under the tubes I provide a suitable swaging mechanism 18 which consists of jaws 19 and 20 pivoted at 21 and actuated by the mechanism 35 which will be hereafter described. The inner surface of jaws 19 and 20 is circular and is adapted to conform with the finished ring.

Jaws 19 and 20 are mounted upon, and are preferably integral with, pivoted plates 23 which are provided with J shaped slots 24 at their outer edges as shown in Figures 2 to 5. Slots 24 slide on pins 25 carried by links 26 which are, in turn, pivoted by pins 27 to bar 28. Bar 28 is mounted on the end of piston 29 and is reciprocated thereby. A suitable spring 30 urges the links 26 toward bar 28 and a suitable linkage system 31 is adapted to push links 26 upwardly against the tension of spring 30.

The operation of the apparatus may be briefly described as follows: The fork supports the hot bar 13 under pipe 10 in the path of jaws 19 and 20, as shown in Figure 2. On the first upward stroke of piston 29 the bar is bent into a U shape, as shown in Figure 3. When the piston is re-

tracted, pins 25 are directed from the outside of the J slot to the inner short leg of said slot, as shown in Figure 4. This changes the point of application of force on jaws 19 and 20 and enables 5 the continued operation of piston 29 to swage the bar around the tube, forming a true ring (see Figure 5).

If desired, the ring may be swaged around a 10 separate mandrel and then slipped over the pipe and welded. In any event, it is desirable to use a weld which is substantially the same width as the thickness of the ring and I prefer to provide the inside of the ring with a tapered edge 15 33 so that the peripheral notch is left to be filled by the welding process. The peripheral notch shown in Figure 7 is desirable in that it enables the weld to be made from one side only. Where 20 the rings are so spaced to permit welding on both sides, they may be beveled, as shown in Figure 8; in this case, beveled edges 34 form annular 25 notches on both sides of the ring which may be filled by the weld 32. During the welding process it is usually desirable to weld the abutting 30 ends of the bar so that the ring is substantially one piece and integral with the tube. Rings attached in this manner add a great deal of strength to the tubes, especially when closely spaced. When the tubes are for use in high pressure systems, this is especially important.— 35 tubes designed to withstand 3000 pounds per square inch must be thick, heavy and cumbersome unless they are reinforced by integrally welded steel rings or equivalent structure.

The provision of a relatively wide welded area 35 is an important feature of my invention since I have discovered that substantially all of the heat

transfer is through the weld and that rings which are shrunk on become comparatively ineffective as heat transferring media. It should be noted that the steel rings are of substantially the same composition as the tubes and that there is, therefore, no appreciable difference in their coefficients of expansion. This avoids the internal stresses which are so troublesome and costly when cast iron gills are used. It should be further noted that the rings may be relatively light 10 and thin and at the same time very effective as reinforcing means and heat transfer means. 15

While I have described a preferred embodiment of my invention it is understood that I do not limit myself to the details hereinabove set forth except as defined by the following claim.

I claim:

In high pressure heating equipment of the type used in oil preheaters in the oil industry, a tube of alloy steel for withstanding high pressure 20 at the high temperatures to which it is subjected in the preheater, a plurality of rings of substantially the same alloy encompassing the tube at regular intervals apart from one another, each 25 of said rings being welded to said tube to form a bond between each ring and the tube entirely encompassing the tube and of a width substantially equal to the width of the inner-most and adjacent wall of the ring so that the tubes and 30 rings are substantially integral whereby maximum heat transfer may be obtained and whereby by the bond, as well as the ring, may serve to strengthen the tube to withstand said high pressure thereby obviating the necessity of providing excessively thick tube wall structure. 35

AUGUSTUS P. McCORMICK.
